(57) **CLAIM**

The ornamental design for an electrical connector, as shown and described.

DESCRIPTION

FIG. 1 is a front, top and right side perspective view of an electrical connector showing my new design;

FIG. 2 is a top plan view thereof;

FIG. 3 is a bottom plan view thereof;

FIG. 4 is a front view thereof;

FIG. 5 is a rear view thereof;

FIG. 6 is a right side view thereof, the left side view is a mirror image thereto;

FIG. 7 is a front, bottom and right side perspective view thereof, in use condition; and,

FIG. 8 is a front, top and right side perspective view thereof, in use condition.

The broken line of the environment shown in FIGS. 7 and 8 is unclaimed subject matter and forms no part of the claimed design.
